INDEX FILE

Charles A. Finley and Ellsworth G. Layer, Tonawanda, N. Y., assignors to Remington Rand Inc., Buffalo, N. Y.

Application November 6, 1931, Serial No. 573,500

10 Claims. (Cl. 49—102)

This invention relates to filing devices and it has particular relation to card index filing devices in which record members are removably mounted in a collapsible supporting structure and members are provided for holding the supporting structure in non-collapsible position.

In certain classes of filing systems it is desirable to replace or remove data sheets, cards, or the like, and yet maintain an efficient and conveniently accessible file; for example, the general class of files employed in the use of toll rate units in telephone switch boards. The invention constituting the subject matter of this application relates generally to this type of file, but the invention is likewise applicable to any kind of filing system requiring removable record members and visible index tabs.

For a better understanding of the invention reference may now be had to the accompanying drawings forming a part of this specification of which,

Fig. 1 is an exploded perspective of the several sections of a filing cabinet embodying the invention;

Fig. 2 is a diagrammatic side elevation of one of the sections of the filing cabinet with record members inserted therein;

Fig. 3 is a plan of the filing unit with the sections thereof assembled but with the tops thereof omitted;

Fig. 4 is a diagrammatic cross-section taken substantially along the line IV—IV of Fig. 2; and

Fig. 5 is a fragmentary cross-section, on a larger scale, taken substantially along the line V—V of Fig. 3.

Referring to the drawings in detail it will be observed that a filing cabinet 10 shown in assembled relation in Fig. 2 is composed of two telescoping sections 11 and 12. The inner section 11 is provided with a rectangular base 14, a pair of side walls 16 and 17, and an end wall 18, the latter having a slot 19 formed centrally therein. Both side walls are provided with beveled end portions 20 and offset flanges 22 along their outer edges. A hinge 23 pivotally secures one edge of the side wall 17 to the base 14 in such manner that this side wall can be swung open to the position shown by the full lines of Fig. 1, or closed against the end wall 18 to provide a trough like configuration of the section 11. The side wall 16 and the end wall 18 are rigid or integral with the base 14.

A row of wires 24 extends rigidly from the side wall 16, this row being disposed along a line diagonally of the wall and substantially parallel

to the beveled edges 20 of the section 11. These wires are provided with thin flat heads 25 and they extend through openings 27 in the wall in such manner as to project across the interior of the section 11 and each wire extends into one of a row of openings 28 in the wall 17 aligned with the row of openings 27. A washer 29 surrounding each wire clamps firmly against the wall in opposed relation to the head 25.

Each of the wires is adapted to support a plurality of record members 30 having clips 32 attached to corresponding edges thereof that are provided with eyelets 33 through which the wires extend. The edges of the record members opposite the clips are offset to provide tab portions 34 and suitable index tabs 36 are attached to the latter edge portions. According to Fig. 3 the record members are arranged in such manner as to illustrate the relation of the clips when the wires accommodate a plurality of the card index record members.

The section 11 in the form described is slidable in the receiving shell section 12 and is guided therein by means of rigid side walls 37 having inwardly turned guiding flanges 38 that engage over the offset flanges 22 of the section 11. These walls have beveled edges 35 corresponding to the edges 20 of the ends of the walls of the section 11. The hinged side wall 17 of course is moved to the position shown in broken lines of Fig. 1 preparatory to the telescoping of the two sections.

An end wall 39 of the section 12 is provided with an angular bracket 40 secured, as indicated at 42, to the wall and including a tapered end 43 projecting toward the central portion of the section 11 at right angles to the end wall. A hook portion 44 is formed at the lower edge of the tapered end 43 adjacent the end wall 39 of the section 12, and the tapered end extends through the slot 19 in the other section in assembled relation for the purpose of engaging the hook portion with the portion of the wall in which the slot is formed. Thus the sections are removably secured together.

In order to secure proper engagement of the bracket 40 in the slot 19, a leaf spring 46, secured as indicated at 47 in the bottom of the shell section 12 is inclined upwardly and rearwardly underneath the bracket 40. When the section 11 is telescoped into the section 12 the base 14 engages the spring and the latter yieldably urges the section 11, upwardly thereby insuring an automatic snap action of the bracket as it engages in the slot. By depressing the section 11 against the force of the spring the hook portion 43

30

35

40

may be released and the section 11 removed from the shell section 12.

A suitable protecting cover 48 is hinged, as indicated at 49, to the top of the rear wall 39 of the shell section 12. This covering can be in the form of a celluloid envelope or the like, and normally rests upon the top of the assembly of record members 30. From this description it will be apparent that the record members can be mounted upon and removed from the wires with very slight delay, and that the arrangement of the wires is such that the tab end of the record members are visible in stepped relation. It is only necessary to depress the section 11 and withdraw it from the section 12 in order to free the hinged wall 17, which may drop by gravity to an inoperative position or can be swung from the ends of the wires with minimum inconvenience.

Although only one form of the invention has been shown and described in detail it will be apparent to those skilled in the art that the invention is not so limited but that various changes may be made therein without departing from the spirit of the invention or from the scope of the appended claims.

We claim:

1. A filing device comprising a plurality of detachably assembled sections, and a plurality of record member supports on one of the sections, portions of one of the sections being collapsible to present record members for replacement, the collapsible portion being held against collapsing in the assembled relation of the sections.

2. A filing device comprising a pair of sections having cooperating assembling parts, record member supports for presenting record members in visible index form, and means for securing the record member supports to one of the sections, one of the sections having a hinged portion cooperating with the record member supports to facilitate removing and installing record members on the support, said hinged portions being closed against removal of the record member when the sections are in assembled relation.

3. A filing device comprising a pair of sections having cooperating assembling parts, record member supports for presenting record members in visible index form, means for securing the record member support to one of the sections, one of the sections having a hinged portion cooperating with the record member supports to facilitate removal and application of record members with respect to the record member supports, and means for releasably locking the sections in assembled relation.

4. A filing device comprising a pair of sections having cooperating assembling parts, record member supports for presenting record members in visible index form, means for securing the record member supports to one of the sections, one of the sections having a hinged portion cooperating with the record member supports to facilitate removal and application of record members with respect to the record member supports, and means for releasably locking the sections in assembled relation, said means including a device for yieldably maintaining the assembled sections in locked relation.

5. A filing device comprising a pair of telescoping sections having guiding members to facilitate assembling the sections, a row of record member supports for presenting record members in visible index form, and means for securing the record member supports to one of

the sections, one of the sections having a hinged portion cooperating with the record member supports to facilitate removal and installation of the record members with respect to the record member supports.

6. A filing device comprising a pair of trough like telescoping sections, one side of one of the sections being movable, guiding portions disposed along the trough-like sections to facilitate the telescoping thereof, and a row of record member supports aligned substantially diagonally of one of the section walls, said movable section side having means for receiving portions of the record member supports, said movable section side being movable to expose the record member support to facilitate the removal of record members therefrom when the sections are disassembled.

7. A filing device comprising a pair of trough-like telescoping sections, one side of one of the sections being movable, cooperating guiding portions disposed along the trough-like sections to facilitate telescoping thereof, a row of record member supports projecting rigidly from one side of one of the trough-like sections, a hook on one of the sections for snapping into engagement within a portion of the other section when the sections are in assembled relation, and resilient means for yieldably maintaining the hook of the one section locked into the other section.

8. An index file, comprising an outer section having a bottom, side walls and one end wall, inwardly extending guide flanges on the upper free edges of said side walls, a catch on said end wall, an inner section having bottom, side walls and one end wall, said inner section having detachable sliding engagement in the outer section through the open end of said outer section, said sections having the side walls, bottom and end wall of each lying adjacent to one another in assembled relation with the free edges of the side walls of the inner section slidably engaged under said guide flanges, the end wall of said inner section having a slot to receive said catch, said inner section having sufficient movement laterally to the direction of its sliding movement in the outer section to engage and disengage a portion of the end wall adjacent said slot with said catch, resilient means for normally holding said inner section engaged with said catch, and a plurality of index cards mounted in said inner section in offset overlapping visible indexed relation.

9. An index file, comprising an outer section having a bottom, side walls and one end wall, inwardly extending guide flanges on the upper free edges of said side walls, an inner section having bottom, side walls and one end wall slidably engaged with said outer section through the open end thereof with the upper free edges of the side walls slidably engaging said guide flanges, said sections having the side, end and bottom walls in adjacent relation when assembled with the outer section housing the inner section, a plurality of index cards mounted in said inner section in offset overlapping visible indexed relation, and means for latching the inner section to the outer section in the assembled relation of said sections.

10. An index file, comprising an outer section having a bottom, side walls and a rear wall, inwardly extending guide flanges on the upper edges of said side walls, an inner section detachably

and slidably engaged in said outer section through the open end thereof, said inner section having means adjacent the side walls of said outer section engaging between said guide flanges and the bottom of said outer section and slidably guiding said inner section in said outer section, means on said inner section for mounting a plurality

of index cards in offset overlapping visible indexed relation, and latching means for locking said inner section in housed relation in said outer section against sliding movement.
